HEATING AND VENTILATING MEANS FOR BUILDINGS

Filed Aug. 1, 1923

Patented Sept. 15, 1925.

1,553,507

UNITED STATES PATENT OFFICE.

HARRY E. CAMPBELL, OF BALTIMORE, MARYLAND, ASSIGNOR TO CAMPBELL METAL WINDOW CORPORATION, OF BALTIMORE, MARYLAND, A CORPORATION OF MARYLAND.

HEATING AND VENTILATING MEANS FOR BUILDINGS.

Application filed August 1, 1923. Serial No. 655,102.

To all whom it may concern:

Be it known that I, HARRY E. CAMPBELL, a citizen of the United States, residing at Baltimore city, State of Maryland, have invented certain new and useful Improvements in Heating and Ventilating Means for Buildings, of which the following is a specification.

This invention pertains to heating and ventilation of buildings, and has for its objects the better utilization of space; the elimination of some or all of the usual radiators from the floors and walls of a building; the delivery or application of heat at the points where the cold of the external atmosphere is now most effective and difficult to counteract; and the warming of the glass of the windows so that snow, ice, and moisture will be prevented from lodging upon and clouding the same.

To these ends the invention consists in providing hollow or box-like window frames with the interior space sufficient to contain the usual sash-weights, if such be used, and pipes or conductors for carrying steam, hot water, or other heating medium; in furnishing said frames with registers or openings through which air, warmed by contact with and radiation from the pipes or conductors, may be delivered into the room or rooms, or spaces to be heated; and in providing controllable inlets and passages for entrance of fresh air from outside the building, and if desired, for escape of vitiated or impure air from within the same.

The manner of carrying out my invention will be explained in connection with the accompanying drawings, which illustrate one embodiment thereof, but it is to be understood that while I deem this a quite satisfactory construction, details may be varied considerably if the general principle and features be retained. In said drawings:

Figure 1 is a front elevation of a window frame equipped with heating pipes, the frame being partially broken away to expose the pipes, the covered portions of which are indicated by dotted lines;

Figure 2 is a horizontal section on the line 2—2 of Fig. 1, a portion between the sides being broken away to permit the parts to be shown on an adequate scale;

Fig. 2^a is a similar view but showing single- instead of double-glazed sash.

Figure 3 is a vertical section on the line 3—3 of Fig. 1, a portion intermediate the sill and head or top of the frame being similarly broken away or omitted.

Describing the figures more in detail, 1 indicates a window frame formed of iron, steel, or other plate or sheet metal, pressed or fashioned to produce a hollow or box-like frame of the required dimensions. The frame may be formed of more or fewer pieces according to its size and to the relative convenience of bending, pressing or shaping a single piece of metal, or producing the frame or any given part or parts thereof of separate pieces united by means of rivets, bolts, or other fastenings. Or the parts may be electrically welded. Cast metal frames may be employed, but the use of plate or heavy sheet metal is deemed preferable on account of lightness, and cheapness of construction when proper equipment for quantity production is provided. The particular manner of forming the frame is not important and is not a feature of the invention here claimed, but material requirements are that the frame shall be of suitable dimensions for the particular place or opening in which it is to be used, and that the cross section of the upright side members 2 and 3 shall be such as to afford adequate space for the sash-weights and their cords or chains, and for the housing of pipes 4 or equivalent conducting and radiating bodies, to heat and cause circulation of a considerable body of air.

The frame 1 will be formed or furnished with vertical runways for the upper and lower sash, if the double-hung sash be employed, though of course the frames may be adapted to receive hinged or swinging sash. In the drawings, however, (see Fig. 2) the upright side members 2 and 3 are represented as formed with a small secondary box 5, the outer or exposed wall of each of which is vertically slotted to receive and guide a tongue or bar 6 extending from top to bottom of each sash frame 7. Said frames will be made of metal, and may be double-glazed as seen in Fig. 2, or single-glazed as seen in Fig. 2^a. Where double-glazed sash are employed, openings 8 will be left in the side bars of the frame, through which warm air may enter between the panes of glass, the latter being separated to afford an air space.

The air being confined in said space, or capable of moving into and out of the same only slowly, forms an insulating body which retards the transmission of heat. The introduction of warm air into the space between the inner and outer panes of glass precludes the deposit thereon of snow or frost, the temperature of the outer glass being thus kept materially above the freezing point, and serving to thaw or melt any snow or ice which may settle or tend to form thereon. It also tends to dry off rain or moisture falling upon the glass.

To permit air to enter and to escape from the upright side members 2 and 3 of the window frame, the opposed or weather faces of said members are cut away as seen in Figs. 2 and 2^a, to form openings 9 which may extend the full length of the side members, or 20 may be in two separated lengths, one above and the other below the level of the meeting rails of the sashes. In Fig. 3 the opening 9 is shown extending from top to bottom of the window frame 1, and air hence enters the 25 upright side members of the frame in the lower portion thereof, moves upward in contact with the pipes or conductors 4, thereby being heated and expanded, and flows outward through said opening in its upper part. Obviously, separate openings at the lower 30 and upper part of the frame may be employed.

To prevent the entrance of floating matter and light objects into the open frame, the 35 openings 9 are advisably protected by wire guards or screens 10. These may be of any desired construction and applied in any usual or convenient way. I prefer, however, to apply to the longitudinal edges of the 40 screens 10, metallic sustaining strips 11 and 12 of the form illustrated in Fig. 2. The strip 11 is produced from a piece of sheet metal longitudinally bent to form a flange 13 perpendicular or at a right angle to the 45 body of the strip, at one side thereof, and is given a second right angle longitudinal bend in the reverse direction, the second flange so formed being folded back upon itself at or about its medial line, producing a U-shaped 50 binder 14 to receive one longitudinal edge of the screen 10. The folded portion of binder 14 may be crimped or compressed upon the screen material to firmly grasp and hold the same, or it may be soldered, riveted 55 or otherwise fastened thereto. It is preferred, however, to employ screws 15 passing through one wall and entering tapped holes in the other wall of the folded binder 14, so that by removing the screws the edge 60 of the screen may be withdrawn from its seat in the folded binder, and the latter left in position on the window frame. The strip 11 so formed and applied thus serves both as a binder or holder for one side of the screen 65 10, and as a retaining and guiding member

for the inner sash frame 7, as will be seen in Fig. 2. The flange 13 is provided with holes at intervals to receive screws 16 which enter tapped holes in the upright wall 17 of the secondary box 5.

The strip 12 applied to the other longitudinal edge of the screen 10 is formed of a piece of sheet metal, one longitudinal edge of which is turned or folded back upon the body to a line about midway between the bend and the opposite edge of the strip, thus forming a strip of hook shape in cross section, adapted to engage with a similarly formed or folded edge 18 of the metal of the window frame 1 bounding the opening 9. The strip 12 may be secured to the screen 10 in any convenient way, as by soldering, by rivets and washers, or the like. Under this construction and arrangement the screen will be securely held in place, yet may be readily removed by simply withdrawing the screws 15, thus releasing the inner edge of the screen and permitting the strip 12 to be drawn outward and disengaged from the folded edge 18 bounding the opening 9.

With the opening or openings 9 arranged as above described and without other air inlet, the air entering and leaving the window frame would be used continuously or for a long time without change other than such as is incident to the inevitable openings present in different parts of a building, due to open flues, imperfect fitting of sash frames and doors, and other well-known causes. It is, however, desirable to maintain a constant inflow of fresh air and discharge of vitiated air, and this may be accomplished simply and effectively by providing air inlets in the sill portion or lower part of the window frames 1, communicating or capable of being put into communication with, the upright side members 2 and 3 of the window frame through movement of suitable valves, registers or dampers.

A simple and convenient construction to this end is illustrated in Fig. 3, where the hollow base or sill portion 19 is shown with an air inlet 20 at its outer or weather side, an opening 21 at its inner side to permit the direct flow of air into the interior of the building, and a controlled port or passage 22 at each side of the window frame, said passages permitting communication between the interior of the hollow sill 19 of the window frame and the upright passages of the side members 2 and 3. To prevent or permit at will the direct inflow of air through passages 20 and 21, I provide a valve or damper 23 which may be furnished with a hinge or hinges 24 at its upper edge, and with an adjusting rod 25 by which to swing it about the pin or pivot of its hinge or hinges. The rod 25 may be notched on its lower side, as seen in Fig. 2, to engage with

a metal plate 26 through which it passes, the notches serving to hold the rod and the valve or damper at any desired adjustment. The openings 22, of which there will be one at either side of the window frame, may each be controlled by a sliding valve or damper 27 having a similar control-rod 28. Suitable guideways for the valve 27 will be provided.

10 By setting the valve or damper 23 in its closed position, as indicated in Fig. 2, direct passage of air from the outside to the inside of the building will be prevented, but by opening the damper more or less a direct 15 inflow of air will be permitted. If both valves 27 be left in the closed position in which one of said valves is shown in Fig. 3, no air can pass from outside the building 20 into the interior of the vertical side members 2 and 3 of the window frame, but by withdrawing either sliding valve 27 more or less, air entering at the port or opening 20 will be permitted to pass in regulated quantity through the opening 22 and into the 25 weight-box or upright passage of the window frame at the side controlled by the valve 27 so opened.

In the drawings I have shown a more or 30 less conventional form or type of radiator or heat conductor, but it is to be understood that this is merely illustrative or suggestive of heat conducting and radiating bodies generally, and subject to variation or change as circumstances shall require or 35 suggest. The designing and proportioning of such apparatus is matter falling within the province of the heating engineer, and determinable largely by the heating medium to be employed, as steam, hot water, or 40 other, and by the relation of the window area to the size or cubic contents of the building, and like factors or considerations.

The piping shown in Fig. 1 comprises a series of separate pipes 4 connected at top 45 and bottom with headers 29 and 30, a pipe 31 connecting the headers 29, a pipe 32 opening from the main 33 into one of the lower headers 30, and a return pipe 34 passing from the other of the lower headers 50 30 back to the boiler supplying steam, for which reason the pipe 34 is shown of smaller diameter as compared with pipe 32 and pipes 4. If hot water be employed, little or no difference in the size of the 55 supply and return pipes will be made. It is possible also to utilize air heated by a suitable furnace or heater, and delivered direct to the window frames, instead of employing steam or water to convey the heat to 60 the frames and transfer it to the air within or passing through the same. I regard steam as the most desirable medium or agent for the purpose, however, since a quite high degree of heat will be required 65 owing to the relatively limited available

space afforded by window frames of permissible dimensions, and to the fact that only the relatively thin glass is interposed between the outside atmosphere and the interior of the building at the points where 70 the heat is initially applied.

Obviously, a like construction may be employed in connection with the frames of doorways and other openings to the atmosphere.

75 The ventilating openings 20 and 21 of the sill portion of the window frame, and if employed, the similar ventilating opening 36 in the top of the window frame, will be protected by wire gauze or netting 80 against the ingress of insects and light floating matter or objects.

The sash designs illustrated in Fig. 3 are of known type, but in the case of the double-glazed sash the filler or spacing strip 85 35 between the two panes of glass will be omitted at intervals on the upright sides of the frame, so that ingress of the heated air shall be possible.

I am aware that it is not broadly new to 90 heat air in the space between the lights of double-glazed sash frames or to deliver heated air thereto, but the general plan of heating by utilization of the box window frames renders such heating of the inter-space peculiarly easy, and adds materially to 95 the efficiency of such general plan.

In the construction illustrated in the drawings, space for the rise and fall of 100 the weights of the two sashes is provided, and the heater or radiator is kept within limits which will leave adequate space therefor. Spring-raised or spring-balanced sashes are, however, used to a considerable extent, and where such are employed, or where the sash frames are hinged, the entire inner space of the upright sides of the window frame may be utilized for the heating or radiating pipes or conductors, as 105 also more or less of the sill and head portions of such frame.

If a warm-air heater be employed, the 110 heated air may be brought direct to and delivered to the interior of the box frame, in which case separate pipes or radiators will not be required. In all cases the window frames themselves radiate more or less heat.

115 It is obvious that modifications may be made in the arrangement of the air inlets and outlets, and a convenient arrangement and one calculated to produce a free and effective flow of the air over the heating pipes or radiators, will be afforded by providing the inlet opening 20 at the outer or weather side of the sill frame, and the outlet opening 36 on the inner side of the head portion of the frame as above noted, so that the fresh air shall enter at the sill, pass 120 into the upright side portions of the frame, and thence to the outlet at its head. In this 125 130

way the air will take the natural line or direction of movement, rising as it becomes warmer, and by reason of the rapid flow taking up quickly the heat of the pipes, and supplying it to the inner space through the opening at the head of the frame. Regulation of the inlet opening 20 or of its communication with the upright portions of the window frame, will render unnecessary a separate valve or damper for the upper opening, though this may be provided if desired.

The main 33 represented in the drawing as a steam pipe is intended to stand for or 15 represent any conduit or main serving to bring steam, hot water, hot air, or other heating agent or medium from a suitable heater to the box window frame.

I claim:

20 1. In a heating plant for buildings, a box frame for a window or opening in the wall thereof, provided in its interior with a heat conductor or radiator, and with openings at or near its lower and upper ends respectively for ingress of cold air and egress of warm air.

25 2. A box frame for door and window openings, provided in its upright portions with runways for sash weights and with 30 pipes or radiators for receiving and conducting a heating medium.

35 3. A box frame for windows and like openings, provided in its interior with pipes or radiators to receive a heating medium, and having openings at its lower and upper parts for ingress and egress of air; and a double-glazed sash frame mounted in said window frame and having openings through its sides communicating with 40 the open spaces of the window frame, through which to receive heated air from the latter.

45 4. A box frame for windows and like openings, containing in its side members heating pipes or radiators, the sill portion of said frame being provided at its outer or weather side and at its inner side with open-

ings for ingress of outside air and delivery of the same to the space within the building; openings in said sill portion of the 50 frame communicating with the hollow side members of the frame to deliver fresh air thereto; and valves or dampers controlling the flow of air from said sill portion of the frame to the side portions thereof and to 55 the interior of the building.

5. A metallic box window frame comprising upright side spaces adapted to contain air; a hollow sill portion communicating with said side portions and provided with 60 an inlet for air; valves or dampers for opening and closing communication between the sill portion and side portions of the frame; heating pipes or radiators located within said side portions of the frame and 65 serving to heat the air entering the same; and an outlet at the upper part of the frame opening to the interior of the building.

6. A metallic box frame for windows and the like, provided with vertically elongated 70 openings in the opposing faces of its upright side members; a metallic retaining and guiding strip secured to said frame at or near one upright boundary of the proximate opening; a screen cover for said opening, 75 detachably secured to said strip; and a second metallic strip secured to the opposite longitudinal edge of the screen cover and folded back upon itself, and engaged with a like folded or hook-shaped edge of the 80 opening, formed upon the box frame.

7. A box frame for windows and the like, having openings at its upper and lower ends respectively for ingress and egress of air; a double-glazed sash frame mounted in 85 said window frame and having openings through its sides communicating with the open spaces of the window frame, through which to receive heated air from the latter; and means for heating the air which enters 90 and passes through the window frame.

In testimony whereof I have signed my name to this specification.

HARRY E. CAMPBELL.
